UNITED STATES PATENT OFFICE.

ARTHUR T. KUEHNER, OF ELKRIDGE, MARYLAND.

LOCOMOTIVE JOURNAL-BOX.

1,288,040.

Specification of Letters Patent. Patented Dec. 17, 1913.

Application filed June 20, 1917. Serial No. 175,903.

To all whom it may concern:

Be it known that I, ARTHUR T. KUEHNER, a citizen of the United States, residing at Elkridge, in the county of Howard and State of Maryland, have invented certain new and useful Improvements in Locomotive Journal-Boxes, of which the following is a specification.

This invention relates to an improved locomotive journal box and has as its primary object to provide a construction wherein lateral play in the drive wheels may be readily taken up as well as an arrangement whereby the side brasses for the journal will be permitted an automatic adjustment as the crown brass of the journal wears.

The invention has as a further object to provide a journal box employing a face plate interposed between the hub of the wheel and the box and wherein the said plate may, when worn, be readily removed and a new plate substituted therefor without displacing the drive wheels.

The invention has as a still further object to provide a construction wherein the face plate will also form flanges at the adjacent side of the box for receiving the wedge and shoe of the box.

A still further object of the invention is to provide a construction wherein the side brasses for the journal will float within suitable channels provided in the box therefor so that as the crown brass wears, the said side brasses may ride vertically within the said channels to thus at all times properly fit against the sides of the journal.

The invention has as a still further object to provide a journal box wherein when the side brasses become worn, liners may be readily interposed between the said brasses and the journal box for taking up such wear.

And a still further object of the invention is to provide a construction wherein the side brasses and the crown brass may all be readily removed when desired.

Other and incidental objects will appear as the description proceeds and in the drawings whereon I have illustrated the preferred embodiment of the invention and wherein similar reference characters designate corresponding parts throughout the several views:

Figure 1 is a fragmentary cross sectional view showing my improved journal box applied to the drive axle of a locomotive,

Fig. 2 is a front elevation of the box detached, this view being partly broken away to show the mounting of the side brasses of the box.

Fig. 3 is a vertical sectional view particularly illustrating the tensioning springs for the side brasses as well as the cap plate employed for holding the side and crown brasses in position.

Fig. 4 is a fragmentary side elevation partly broken away to show the mounting of the face plate of the journal box, the plate in this view being lifted so that the bolts normally holding the said plate may be disengaged therefrom, and

Fig. 5 is a rear elevation showing the mounting of the cap plate for the brasses of the box.

In carrying out the invention, my improved journal box is formed with a body 10 having a recess through the lower side thereof for receiving the journal 11 of the drive axle 12. The axle has been conventionally shown for convenience and carries the drive wheels 13. Mounted in the lower portion of the journal receiving recess of the box in any approved manner is a cellar 14 which has also been conventionally shown. This cellar may be of any approved type and is detachably held in position by transverse rods 15 connected with the lower end of the journal box.

At its inner side the body 10 of the box is formed with lateral flanges 16 engaging one with a wedge 17 and the other with a shoe 18 for the box. The wedge and shoe are also conventionally shown and may be of any approved type, the wedge being mounted for vertical adjustment in the usual manner. Receiving the wedge and shoe are the sides of the pedestal for the box, as conventionally shown at 19, the wedge and shoe being each channel shaped in cross section to engage around the sides of the pedestal.

Upon its inner side the body 10 of the box is cut away to provide oppositely disposed horizontal channels 20 and above the said channels is further recessed to form a crown brass seat 21 separated from the channels 20 by horizontal ribs 22. In this connection, it will be observed that the channels 20 open through the inner and outer side faces of the body 10 of the box. Removably fitted within the said channels are

side brasses or bearings 23 for the journal of the axle. These brasses upon their inner faces are formed to fit around the said journal at the central portion thereof and are mounted to slide vertically within the channels. Bearing between the upper edges of the brasses and the ribs 22 are bowed springs 24. These springs are, as particularly shown in Fig. 3 of the drawings, arranged to normally hold the side brasses against rattling. Removably fitted within the seat 21 is an arcuate crown brass 25 for the box formed to fit over the upper portion of the journal 11 and resting at its ends upon the ribs 22.

It will now be observed that the side brasses 23 present a relatively large bearing area to the journal for taking care of the horizontal forces exerted against the said brasses, while at the same time the crown brass 25 is mounted to effectually support the load. When the side brasses 23 have become worn liners 26 may be interposed between the said brasses and the bottom walls 20 of the channels 20 for spacing the brasses laterally and taking up such wear. The journal box at the left of Fig. 1 is shown equipped with these liners 26 while the journal box at the right is shown without the liners. As the crown brass 25 wears, the journal 11 of the axle will, of course, move upwardly within the box and the particular function of the springs 24 of the side brasses 23 now becomes apparent. It will be seen that as the journal thus moves upwardly, the side brasses will be permitted to float upwardly or vertically within the channels 20 therefor against the tension of the springs 24 to thus follow the journal upwardly within the box and consequently at all times maintain a proper horizontal position with respect to the journal to bear against the sides thereof. In this way automatic adjustment of the side brasses is permitted.

Seating against the outer sides of the body 10 of the box is a face plate 27 formed, as particularly shown in Fig. 2, to removably fit around the journal 11 of the axle and overlie the outer ends of the side and crown brasses 23 and 25 for holding the said brasses against outward displacement. The plate 27 is formed to overhang the ends of the box body to provide, as clearly shown in Fig. 1, lateral flanges arranged to cooperate with the flanges 16 of the body of the box in receiving the wedge and shoe 17 and 18 respectively with the said plate fitting snugly between the outer side of the box and the wheel hub. Thus, the plate will receive the wear of the wheel hub and hold the drive wheels against lateral play. Loosely fitting through the body 10 of the box are a plurality of bolts 28 provided at their outer ends with heads 29 and receiving nuts 30 at their inner extremities. As particularly shown in

Fig. 4, the nuts 30 of the said bolts are preferably countersunk in the inner side of the box body. The bolts 28 are preferably arranged one adjacent each of the corners of the body of the box and, as shown in Fig. 2, 70 are formed with flat sides for holding the bolts against rotation. At their outer extremities the bolts 28 project freely through key-hole slots 31 in the plate 27 and engage by the heads 29 thereof within the said slots 75 for firmly connecting the plate with the body of the box and rigidly holding the said plate to receive the wear of the adjacent wheel hub. However, in order to relieve the said bolts of a portion of the stress upon the 80 plate, the said plate is, upon its inner side, formed with an arcuate lateral shoulder 32 engaging within the crown brass seat 21 for rigidly supporting the plate against lateral as well as upward movement. The shoulder 85 32 is, as particularly shown in Fig. 3, preferably very narrow, for a reason which shall presently appear.

Attention is now directed to the fact that when the plate 27 has become worn, the nuts 90 30 of the bolts 28 may be loosened to relieve the tension of the bolts upon the said plate so that the plate may, as illustrated in Fig. 4, be lifted to dispose the heads 29 of the bolts opposite the lower larger ends of the 95 key-hole slots 31 in the plate. The bolts 28 may then be withdrawn through the body of the box to seat the heads thereof within suitable recesses 33 formed in the outer side of the box body to receive the said bolt heads. 100 The plate 27 will then be entirely free so that the said plate may be consequently lifted upwardly and removed. The purpose in forming the shoulder 32 of the plate relatively narrow will now appear since it will 105 be seen that in order to thus lift the plate upwardly the said shoulder must be first disengaged from the body of the box by swinging the plate outwardly and since the space between the outer side of the box and the 110 wheel hub is of course restricted, only a slight outward movement of the plate will be permitted. It will thus be seen that when the plate 27 has become worn, a new plate may be readily substituted therefor for taking up any lateral play in the drive wheels. Furthermore, this result may be accomplished without displacing the wheels or removing the journal box.

Connected to the inner side of the body 10 120 of the journal box is a cap plate 34 constructed to conform to the outline of the journal receiving recess in the box. This plate is formed to loosely receive a plurality of bolts 35 set into the rear side of the box 125 body and is engaged by the nuts 36 of the said bolts for detachably holding the said plate in position. Extending from the upper portion of the plate is an arcuate lateral flange 37 fitting into the crown brass seat 21 130

to engage the wall thereof and bearing against the adjacent end of the crown brass 25 for holding the said brass in position. The side portions of the plate are, as clearly shown in Fig. 3, provided with lateral flanges 39 fitting within the channels 20 for the side brasses to seat against the bottom walls thereof and engage the inner extremities of the side brasses 23 for holding these brasses in position. At the same time, the flanges 39 of the plate as well as the flange 37 thereof, will act to reinforce the plate and will co-operate with the bolts 37 for firmly holding the plate upon the body of the box.

As will now be clear, the side brasses 23 and the crown brass 25 may be readily removed by simply detaching the plate 34. Thus, the brasses of the box may be renewed without the necessity of displacing the box.

Moreover, this construction also provides a simple means whereby the liners 26 may be readily fitted in position, the plate 34, of course, normally acting to hold the said liners against inward displacement.

It will therefore be seen that I provide a particularly efficient construction for the purposes set forth and an arrangement wherein all the parts of the journal box subject to wear may be readily replaced without the necessity of removing the box or displacing the wheels. In this connection it will be observed that the cap plate 34 is arranged to overhang the inner ends of the springs 24 and will thus normally hold the said springs against inward displacement while the bowed portions of the springs are engaged within suitable arcuate recesses 24' in the lower faces of the ribs 22 for holding the said springs against lateral movement toward the journal. The springs will thus at all times be effectually supported to co-operate with the side brasses 23 to prevent the rattling or chattering of the brasses while, at the same time, the said brasses may move upwardly within the box against the tension of the said springs when the box is shifted downwardly with respect to the journal. It is also to be observed that my improved journal box provides a construction wherein the frames or pedestals may be kept in alignment at all times since, in order to line the wedges and shoes, it will not be necessary to remove the pedestal braces. Upon disconnecting the plates 27, the journal boxes may then be shifted inwardly upon the journals when the wedges and shoes may be displaced and liners inserted between the said wedges and shoes and the sides of the pedestals. This done, the boxes may then again be fitted in position and the face plates secured in place for connecting the journal boxes with the pedestals. Obviously, this feature of the present construction provides a very advantageous arrangement.

Having thus described the invention, what is claimed as new is:

1. A journal box of the character described including a body, a face plate seating against the outer side thereof, and means detachably connecting the said plate with the body and retractable to permit the displacement of the plate from the body in a plane parallel therewith.
2. A journal box of the character described including a body, a face plate seating against the outer side thereof, and means detachably connecting the said plate with the body and retractable through the body to a position whereby the plate may be displaced from the body in a plane parallel therewith.
3. A journal box of the character described including a body, a face plate seating against the outer side thereof, and means engaging through the said plate and detachably connecting the plate with the body, said means being shiftable inwardly upon the body to permit the upward displacement of the plate from the body.
4. A journal box of the character described including a body, a face plate seating against the outer side thereof and means fitting through the body to engage through the said plate for detachably connecting the plate with the body, the plate being shiftable to permit the retraction of the said means upon the body and the removal of the plate from the body.
5. A journal box of the character described including a body, a face plate seating against the outer side thereof, and formed with a key-hole slot, and a bolt fitting through said slot and engaged with the body for detachably connecting the plate thereto, the plate being shiftable upon the body to permit the retraction of the bolt through the said slot for freeing the plate.
6. A journal box of the character described including a body, flanges formed thereon, and a face plate connected to one side of and overhanging the body to provide flanges arranged to co-operate with said first-mentioned flanges for operatively receiving a pedestal for the box.
7. A journal box of the character described including a body, flanges formed thereon, and a face plate detachably connected to the outer side of and overhanging the body to provide flanges arranged to co-operate with said first-mentioned flanges for operatively receiving a pedestal for the box, the said plate being removable from the box in a plane parallel thereto.
8. A journal box of the character described including a body recessed to receive a journal, a face plate seating against the outer side of the body, means detachably connecting the said plate to the body, and a shoulder formed on the body and engaging

within said recess to coöperate with the said means for normally holding the plate rigidly against movement upon the body.

9. A journal box of the character described including a body provided with a recess in the outer side thereof, a face plate overlying the outer side of the body and provided with a slot, and a bolt fitting through said slot and provided with a head

engaging with the plate for detachably connecting the plate with the body, the plate being shiftable upon the body to permit the retraction of the bolt head through the said slot into said recess whereby the plate may be removed from the body in a plane parallel therewith. 10 15

In testimony whereof I affix my signature.
ARTHUR T. KUEHNER. [L. s.]
